BENJAMIN DARLING, OF BRIDGEWATER, MASSACHUSETTS.

Letters Patent No. 83,261, dated October 20, 1868.

IMPROVEMENT IN BIT-STOCKS.

The Schedule referred to in these Letters Patent and making part of the same.

To all whom it may concern:

Be it known that I, BENJAMIN DARLING, of Bridgewater, in the county of Plymouth, and State of Massachusetts, have invented a new and useful Improvement in Bit-Stock; and I do hereby declare that the following is a full, clear, and exact description thereof, which will enable those skilled in the art to make and use the same, reference being had to the accompanying drawings, forming part of this specification.

The object of this invention is to construct a bit-stock, so that the shank of the bit or boring-auger may be firmly held, without the use of springs or screw-nuts, and so that the bits or augers may be used without altering their shanks, or filing them in any manner.

And the invention consists in the use of sliding jaws, and in the manner in which they are operated, as I will proceed to describe.

Figure 1 represents a longitudinal view of the stock, showing the method of operating the sliding jaws.

Figure 2 is a section through the line $x x$, giving a side view of the jaws, and showing the manner in which they grasp the shank of the bit.

Figure 3 is a top view of the jaws and compressing-band.

Similar letters of reference indicate corresponding parts.

A is the stock, which is made with a socket in its end for receiving the shank of the bit, as seen in fig. 2.

B B represent the sliding jaws.

These jaws enclose the socket-shank of the stock, and, passing below it, are attached to a lever, C, at c'.

D is the fulcrum of the lever, which is on a projecting arm, E, of the stock A.

F represents an elongated band, which is formed on or attached to the socket-end of the stock A.

The jaws B B pass through the apertures g g on the sides of the socket-end, as seen in the drawing.

The outer sides of the jaws form inclined planes, h h, which inclined surfaces are in contact with the outer portions of the apertures g g, so that when, by the action of the lever C, the jaws are drawn downward, the jaws are brought together or approach each other so as to grasp the shank of the bit.

The jaws, by their shanks, are loosely attached to the lever C, and while they have sufficient play in the band-apertures g to allow of their expansion and contraction by their sliding movement, all lateral movement is prevented by the band.

The lever C is kept in place (when the bit is fastened) by the lugs i on the stock, there being sufficient lateral play or spring allowed to the lever for this purpose.

There may be a little flexibility allowed to the shanks of the jaws, which would cause the i to open and expand when they are raised, but that is not deemed essential.

The sliding motion of the jaws may be produced otherwise than by a lever, as, for instance, by a screw or a cam.

I do not, therefore, confine myself to the use of a lever for that purpose, but to any device by which the sliding or longitudinal motion of the jaws may be produced.

The advantages of this arrangement are many and obvious.

Common wood-screws may be held in the jaws, with a short screw-driver in the socket behind the screw, with the bit of the screw-driver in the nick of the screw, so that such screws may be started and partly driven, in situations where it is inconvenient for the operator to use both hands for the purpose of driving the screw.

The rigid fastening, and the ease and rapidity with which a bit is fastened and unfastened, the simplicity and durability of the parts, render this arrangement superior to all others for the purpose intended.

I claim as new, and desire to secure by Letters Patent—

In combination with a bit-stock, the sliding jaws B B, whereby a bit or auger is fastened to the stock, substantially in the manner herein shown and described.

The above specification of my invention signed by me, this 6th day of June, 1868.

BENJAMIN DARLING.
